UNITED STATES PATENT OFFICE.

HAROLD P. FARIS, OF CHICAGO, ILLINOIS, ASSIGNOR TO KROEHLER MANUFACTURING COMPANY, OF NAPERVILLE, ILLINOIS, A CORPORATION OF ILLINOIS.

DESIGN FOR A CHAIR.

Application filed February 18, 1928. Serial No. 25,482. Term of patent 3½ years.

To all whom it may concern:

Be it known that I, HAROLD P. FARIS, a citizen of the United States, residing at Chicago, in the county of Cook and State of Illinois, have invented a new, original, and ornamental Design for Chair, of which the following is a specification, reference being had to the accompanying drawing, forming a part thereof.

The figure is a perspective view of the chair, showing my new design.

I claim:

The ornamental design for a chair, substantially as shown.

HAROLD P. FARIS.
